3,401,337 A 9/1968 Beusman et al.
3,484,681 A 12/1969 Grady, Jr. et al.

CLAIM

The ornamental design for a display screen or portion thereof with graphical user interface for a medical device, as shown and described.

DESCRIPTION

The sole FIGURE is a front view of a display screen or portion thereof with graphical user interface for a medical device.

In the sole FIGURE, the outermost dot-dash broken line showing a boundary of the display screen or portion thereof forms no part of the claimed design. The remaining dash-dash broken line showing the graphical user interface forms no part of the claimed design.
